234,558

DISPENSER FOR TOILETRIES OR THE LIKE

Philip K. Scheeler, 9350 Lowell Blvd.,
Westminster, Colo. 80030

Filed May 2, 1973, Ser. No. 356,512

Term of patent 14 years

Int. Cl. D6—06

U.S. Cl. D6—95

Fig. 1

Fig. 4

Fig. 6

Fig. 2

Fig. 3

Fig. 5

Fig. 7

FIG. 1 is a front perspective view of a dispenser for toiletries or the like showing my new design,

FIG. 2 is a rear perspective view thereof,

FIG. 3 is a rear elevational view thereof,

FIG. 4 is a top plan thereof,

FIG. 5 is a side elevation view thereof, the opposite side being identical thereto,

FIG. 6 is a top plan view thereof with the cover removed, and

FIG. 7 is a bottom plan view thereof.

I claim:

The ornamental design for a dispenser for toiletries or the like, as shown.
